US00D794051S

(12) **United States Design Patent** (10) **Patent No.:** **US D794,051 S**
(45) **Date of Patent:** **** Aug. 8, 2017**

(54) **DISPLAY SCREEN WITH GRAPHICAL USER INTERFACE**

H04N 21/00; H04N 21/234; H04N 21/431; H04N 21/4312; H04N 21/4314; H04N 21/4316

See application file for complete search history.

(71) Applicant: **Microsoft Corporation**, Redmond, WA (US)

(72) Inventors: **Peter Duyen Hung Hoang**, Delta, CA (US); **Joshua Trusz**, Vancouver (CA); **Garson Kwan**, Redmond, WA (US); **Victor Tran**, Redmond, WA (US); **Preet Mangat**, Redmond, WA (US); **Charla Pereira**, Seattle, WA (US); **Raymond Lum**, Redmond, WA (US)

(73) Assignee: **Microsoft Corporation**, Redmond, WA (US)

(**) Term: **15 Years**

(21) Appl. No.: **29/537,228**

(22) Filed: **Aug. 24, 2015**

CLAIM

The ornamental design for a display screen with graphical user interface, as shown and described.

DESCRIPTION

The FIGURE is a front view of a display screen with graphical user interface showing our new design.

The broken line showing of the remainder of the user interface and the remainder of the display screen is for environmental purposes only and forms no part of the claimed design.

1 Claim, 1 Drawing Sheet
